(57) **CLAIM**

(21) Appl. No.: **29/801,984**

The ornamental design for a face filtration mount for automated filter tester, as shown and described.

(22) Filed: **Aug. 2, 2021**

DESCRIPTION

(51) **LOC (14) Cl.** **10-04**

FIG. 1 is a front perspective view of a face filtration mount;
FIG. 2 is a front elevation view thereof;
FIG. 3 is a rear elevation view thereof;
FIG. 4 is a right-side view thereof;
FIG. 5 is a left-side view thereof;
FIG. 6 is a top view thereof including an indication of a
sectional cut;
FIG. 7 is a bottom view thereof;
FIG. 8 is a rear perspective view thereof; and,
FIG. 9 is a cross sectional view thereof along a sectional cut
depicted in FIG. 6.

(52) **U.S. Cl.** **D10/96**

The broken lines shown in the drawings are only provided
to illustrate the environment of the design, and form no part
of the claimed design.
